CLAIM

The ornamental design for an implement for washing scalp, as shown and described.

DESCRIPTION

FIG. 1 is a top perspective view of an implement for washing scalp;

FIG. 2 is a bottom perspective view thereof;

FIG. 3 is a front view thereof;

FIG. 4 is a right side view thereof;

FIG. 5 is a left side view thereof; and,

FIG. 6 is a bottom plan view thereof.

The broken lines in the drawings depict environmental subject matter only and form no part of the claimed design.
